COMBINED MEMORANDUM SHEET AND PENHOLDER

John J. Olson, St. Paul, Minn., assignor to Brown &
Bigelow, St. Paul, Minn.

Application March 19, 1956, Serial No. 40,671

Term of patent 14 years

(Cl. D74—1)

FIG. 1

FIG. 2

FIG. 4

Fig. 1 is a perspective view of a combined memorandum sheet and penholder, showing my new design, as it appears with the slidable tray in open position;

Fig. 2 is an end elevational view thereof looking from the tray end;

Fig. 3 is a side elevational view thereof as it appears with the tray in closed position; and

Fig. 4 is a top plan view thereof.

I claim:

The ornamental design for a combined memorandum sheet and penholder, as shown.
